(57) CLAIM

The ornamental design for a toothbrush with a ribbon handle, as shown and described.

DESCRIPTION

FIG. 1 is a left side view of our design showing our toothbrush with ribbon handle;

FIG. 2 is right side view thereof;

FIG. 3 is a front view thereof;

FIG. 4 is a back view thereof;

FIG. 5 is a top view thereof; and,

FIG. 6 is a bottom view thereof.

The broken line showing of bristles is included for the purpose of illustrating a portion of the article that forms no part of the claimed design.
